COLON THERAPY APPARATUS

Filed March 25, 1929

INVENTOR.

Maurice H. Kowan
BY Luther Johns.

ATTORNEY.

UNITED STATES PATENT OFFICE

MAURICE H. KOWAN, OF CHICAGO, ILLINOIS

COLON-THERAPY APPARATUS

Application filed March 25, 1929. Serial No. 349,601.

These improvements relate to apparatus, devices or equipment for treating the colon according to a method which in general is well understood. This method proceeds by way of the injection of liquid into the bowel through a catheter followed by the discharge of liquid and bowel contents without removing the catheter, this operation being repeated many times during a single treatment.

More specifically these improvements relate to features of improvement in the operating table and to the mounting of the liquid-control device for vertical adjustments.

The chief objects of the invention are to facilitate the operator's work and improve the results or obtain desired results in various situations, which, while not unusual, are outside the ordinary and in which the desired results cannot be obtained, or else only difficultly obtained, according to the practice heretofore.

One detail of the invention is designed to preserve the table more clean and sanitary and to safeguard the patient from contact with discharged body-cavity contents.

Another specific object is to provide means for injecting and discharging the treating liquid more advantageously.

Other objects and advantages will appear hereinafter.

Figure 1 of the drawings shows the apparatus or equipment complete in side elevation except for the liquid containers and pipe connections therewith; Fig. 2 is a top plan of the apparatus of Fig. 1; and Fig. 3 is a section on the line 3—3 of Fig. 2.

It is old to provide a long and narrow table top as 10 supported as by legs 11, the table top having a toilet seat 12 near one end, with a horizontally disposed one-piece cushion or mattress on the table top, the cushion having a head-rest or pillow, and with a liquid-distributing or control device mounted to swing on arms as 14 and 15, with a catheter 16 and a discharge pipe 17 controlled by a valve as 18, with valves as 19, 20 and 21 controlling the flow of liquid from the several tanks or receptacles. The patent to Shellberg, Number 1,577,876 of March 23, 1926 may be referred to in this connection.

A novel feature herein disclosed is in the

provision of means for elevating a portion or portions of the patient's body above the normally horizontal plane of the cushion according to the particular conditions of a given patient or the varying conditions during a given treatment.

Fig. 1 shows by dotted lines the head-and-shoulder head part 22 and also the lower of abdominal and hip part 22^a of the cushion as being elevated. To this end the cushion or mattress is preferably made in two pieces to provide a desired flexibility at its middle while avoiding destructive bending effects incident to a one-piece construction.

These two cushion parts 22 and 22^a are supported by flat, plate-like members 23 and 24 hinged at 25 not only together but also to the angle-iron side members 10^a of the table top frame whereby these supports 23 and 24 may move upward at their outer ends but may not shift in the main frame.

The means for elevating the supports 23 and 24 respectively are shown as being the same in each instance and may be given the same reference characters. They respectively comprise a vertically-disposed rod 27 having a rack at its lower portion meshing with a pinion 28, a crank arm 29, a ratchet-and-pawl device 30, with a roller 31 at the top of the rod 27 and contacting the bottom of the supports 23 and 24 respectively. The operator may thus raise and lower either end of the cushion or mattress, and to the desired extent.

I have provided at each side of the table a pair of foot- rests marked 32 and which may be of any approved form or construction. They are available to the patient when the cushion 22^a is raised or when it is in its normally horizontal position. They may be swung into an out-of-the-way position beneath the table. Such foot rests are not new in connection with operating tables of one kind or another, but are new, so far as I know and believe, in connection with a treating table of this kind. Similarly it is not novel broadly, in an operating table, to provide means for elevating the patient's head and shoulders or the lower part of his body, but I believe it to be novel to provide such means in connection with such a table in

colon irrigation work. There are certain peculiar advantages and results to be obtained through such provisions.

Turning to the right hand end of Figs. 1 and 2 the liquid-control device marked as a whole 33 is illustrated, described and claimed in my copending application, Serial Number 349,600, filed March 25, 1929. So far as the present invention is concerned the device 35 may be of any well-known or approved type or kind. For example, it may be of the construction shown in the patent mentioned. The invention in this respect is in means for holding the control device 35 bodily in various positions of vertical adjustment for treating results.

To this end the swinging arm 14 is pivotally mounted to swing horizontally at the upper end of a vertically-disposed bar or rod 34 which has a rack 35 at its lower end portion meshing with the pinion 36 rotated by the crank arm 37 while a dog, 38, Fig. 2, is adapted to be swung into engagement with respective teeth of the rack to hold it in any given position of vertical adjustment.

Fig. 3 sectionally shows a construction of the seat 12 providing means for maintaining the under surface of the seat and adjacent parts clean and sanitary. They are shown as comprising an annular recess 40 closely adjacent to the annular narrow surface 41 around the seat opening and providing a narrow edge 42, which is downwardly projecting and in the nature of a projecting flange or rim. Water and other matter which may be upon the seat or come to the seat opening and flow gravitationally downward at the edge thereof drips off of the rim 42 without running around and spreading over the bottom of the seat.

This provision is valuable in any toilet seat construction, but it is of particular importance in a device of the present kind where the upper surface of the seat is quite likely to become contaminated by bowel contents as a result of the operation. A catch basin as 44 with a channel as 45 leading to the seat opening is old. Heretofore discharge matter passing through the channel 45 spread around on the under surface of the seat, and the same is true of water, often contaminated, flowing from the catheter upon the table under some conditions.

The provision of means for elevating and holding the cushion at its ends in various positions of adjustment is important in various respects. As to raising the head portion of the cushion it is pointed out that there are occasions to treat patients having pulmonary or heart affections and wherein the elevated position of the head and shoulders affords relief and enables the operator to proceed with his work. Then too, such an elevated position of the head and shoulders relaxes the abdominal muscles, as does also the

raising of the hips. Such relaxation is highly important in the case of nervous patients, and frequently others who find it difficult at a particular time to relax the abdomen sufficiently for best results.

Raising the hips is important further in the withdrawal of gases from the colon. The advantage is had through the tendency of the gases to rise in the bowel and catheter. This gas removal is a very important factor in the treatment, since they obstruct the injection of treating liquid and cause marked discomfort to the patient.

A further important advantage of the hip elevation is in the injection of treating oils and other medicaments where the quantity of liquid is relatively small and not sufficient to fill the three branches of the colon, but it is yet highly desirable that all three branches receive the treatment. Such treatments with oil or medicaments will occur usually after the bowel has been evacuated to the extent possible or desired. By then raising the hips the treating liquid flows easily into the descending and transverse colon, and then by lowering the hips and turning the patient on his right side it flows into the ascending colon and cæcum.

In order to attain these advantages without undue disturbance of the patient or loss of time to the operator the means for raising and lowering the body as desired are placed under the immediate control of the operator when in his operating station, as by the crank arms at the operating side of the table.

In this same connection the raising and lowering of the liquid-distributing unit 33 is highly important. I have ascertained from experience that the best results are had when the treating unit is slightly above the body cavity opening, say about an inch, especially for the discharge. According to the provisions made in this regard the operator can raise and lower the distributing head or device as desired and without leaving his station.

There are instances in which the distributor as 33 may be raised advantageously without raising the hips, as in the elimination of gases from the body. The operator may raise the device thus temporarily for that purpose and then lower it for further treatment.

With respect to the foot rests 32, it sometimes happens that the patient must be permitted to empty in a natural way while lying flat, the discharge being into the catch basin or recess 44. The foot rests are valuable adjustments thereto, making for convenience and cleanliness.

The foot rests are also of advantage at times in treating in the usual way. Ordinarily the patient's feet come to the edge of the seat opening farthest from the patient

and against which his feet may rest. However, there are times when it is desired to have the patient draw his knees upward and spread them apart, whereupon the foot rests come into use.

It will thus be clear that by these improvements I have provided great flexibility and a variety of novel attributes and features in the treating instrumentalities whereby greatly improved results, and results not hitherto obtained, may be had in a simple, easy and expeditious way.

I contemplate as being included in these improvements all such changes, variations and departures from what is thus specifically illustrated and described as fall within the scope of the appended claims.

I claim:

1. A colon therapy apparatus of the character described comprising a liquid-control device including a catheter and a discharge pipe, with valves for regulating the liquid flow, and an operating table having a toilet seat, a normally-horizontal cushion adjacent to said seat and adapted to support the patient's body between his head and hips with the hips adjacent to said seat and adjacent to one end of the cushion, said distributing device being arranged whereby its catheter is readily applicable to the patient's rectum, said apparatus including also means for holding a portion of said cushion elevated above the normally-horizontal plane of the cushion to hold a portion of the patient's body so elevated for colon treatment.

2. The apparatus of claim 1 hereof in which said means are adapted to hold the head and shoulders of the patient so elevated.

3. The apparatus of claim 1 hereof in which said means are adapted to hold the hips of the patient so elevated.

4. The apparatus of claim 1 hereof in which there are means under the control of the operator at his operating station for raising and lowering said distributing device bodily into various positions of vertical adjustment.

5. The combination of claim 1 hereof in which said table has a foot rest at each side thereof arranged to be engaged by the patient's feet respectively when his hips are in elevated position and also when he is lying substantially horizontally on the table.

6. In a liquid-control device for a body-cavity irrigator of the character described comprising a head adapted to be connected to a plurality of sources of liquid supply, with valves for controlling the flow of the liquids respectively through said head, and comprising also a catheter and a discharge pipe, with valve means for controlling the flow from said head through the catheter and from the catheter through the discharge pipe, the combination therewith of means for holding said con-

trol device bodily in various positions of vertical adjustment.

7. The combination of claim 6 hereof in which there are means under the control of the operator at his operating station for adjustably raising and lowering said control device bodily.
